(57) **CLAIM**

The ornamental design for a bottle for a wild bird feeder, as shown and described.

DESCRIPTION

FIG. 1 shows a front perspective view of a bottle for a wild bird feeder showing our new design.

FIG. 2 is a front perspective view of the bottle for a wild bird feeder;

FIG. 3 is a front elevation view of the bottle for a wild bird feeder, the back side view being a substantial mirror image thereof;

FIG. 4 is a side elevation view of the bottle for a wild bird feeder, the other side view being a substantial mirror image thereof;

FIG. 5 is a top plan view of the bottle for a wild bird feeder; and,

FIG. 6 is a bottom plan view of the bottle for a wild bird feeder.

Broken lines and unshaded portions contained within broken lines are environment only and form no part of the claimed design.
